DESIGN FOR A FUEL SUPPLY UNIT FOR OIL BURNERS

Harrison E. Fellows, Racine, Wis., assignor to
Webster Electric Company, Racine, Wis., a cor-
poration of Wisconsin

Application December 21, 1935, Serial No. 60,329

Term of patent 14 years

To all whom it may concern:

Be it known that I, Harrison E. Fellows, a citizen of the United States, residing at Racine, in the county of Racine and State of Wisconsin, have invented a new, original, and ornamental Design for Fuel Supply Units for Oil Burners, of which the following is a specification, reference being had to the accompanying drawing, forming part thereof.

Fig. 1 is a top plan view of the fuel supply unit;
Fig. 2 is a front elevational view; and
Fig. 3 is a side elevational view.

I claim:

The ornamental design for a fuel supply unit
for oil burners as shown.

In witness whereof, I hereunto subscribe my
name, this 12th day of December, 1935.

HARRISON E. FELLOWS.
